Des. 238,562
Patented Jan. 27, 1976

238,562

TIME TEMPERATURE ANALYZER

Joseph A. Sylvester, Wayne, N.J., assignor to
Hexacon Electric Company

Filed Jan. 14, 1974, Ser. No. 433,419

Term of patent 14 years

Int. Cl. D10—04

U.S. Cl. D10—78

FIG. 1

FIG. 2

FIG. 3

FIG. 4

FIG. 1 is a top plan view of a time temperature analyzer showing my new design in the open position;

FIG. 2 is a left side elevational view thereof;

FIG. 3 is a front elevational view thereof; and

FIG. 4 is a right side elevational view thereof.

The top and bottom of the outside case are substantially flat, plain and inornamented.

I claim:

The ornamental design for a time temperature analyzer, as shown and described.
